(57) **CLAIM**

The ornamental design for a scaffolding hatch deck hinge, as shown and described.

DESCRIPTION

FIG. 1 is a perspective view of a my new design for a scaffolding hatch deck hinge;

FIG. 2 is a right side elevational view thereof;

FIG. 3 is a front view thereof;

FIG. 4 is a rear view thereof;

FIG. 5 is a top view thereof; and,

FIG. 6 is a bottom plan view thereof.

The broken lines shown in the figures are for illustrative and environmental purposes only and form no part of the claimed design.

The boundaries of the claimed design are understood to be located at the edge established by the transition from shaded areas to unshaded areas in the drawing views.
